US0D1036949S

(12) **United States Design Patent** (10) **Patent No.:** **US D1,036,949 S**
(45) **Date of Patent:** **** Jul. 30, 2024**

(54) **GRAPE CUTTER**

(71) Applicant: **Zhen Lin**, Zhejiang (CN)

(72) Inventor: **Zhen Lin**, Zhejiang (CN)

(**) Term: **15 Years**

(21) Appl. No.: **29/920,447**

(22) Filed: **Dec. 11, 2023**

(51) LOC (14) Cl. **07-04**

(52) U.S. Cl.

USPC **D7/669**

(58) **Field of Classification Search**

(57) **CLAIM**

The ornamental design for a grape cutter, as shown and described.

DESCRIPTION

FIG. 1 is a front, left, top perspective view of a grape cutter, showing my new design;

FIG. 2 is a rear, right, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The dashed broken lines illustrate portions of the grape cutter which form no part of the claimed design.

1 Claim, 8 Drawing Sheets
